RAZOR OR SIMILAR ARTICLE

William R. Pomper, Highland Park, Ill.
(140 S. Dearborn St., Chicago, Ill. 60603)

Filed Jan. 5, 1971, Ser. No. 104,192

Term of patent 14 years

Int. Cl. D28—03

U.S. Cl. D95—3

FIG. 1

FIG. 2

FIG. 3

FIG. 4

FIG. 5

FIG. 1 is a perspective view of a razor or similar article showing my new design;

FIG. 2 is a front elevational view, the rear having substantially the same appearance;

FIG. 3 is a side elevational view, the opposite side having substantially the same appearance;

FIG. 4 is a top plan view; and

FIG. 5 is a bottom plan view thereof.

Portions of FIGS. 1, 2 and 3 are stippled to indicate contrast in appearance.

I claim:

The ornamental design for a razor or similar article, substantially as shown and described.
